UNITED STATES PATENT OFFICE.

HERBERT M. KINSLEY, OF CHICAGO, ILLINOIS.

APPARATUS FOR BROILING.

SPECIFICATION forming part of Letters Patent No. 245,925, dated August 16, 1881.

Application filed March 28, 1881. (No model.)

To all whom it may concern:

Be it known that I, H. M. KINSLEY, of Chicago, in the county of Cook and State of Illinois, have invented certain new and useful 5 Improvements in Apparatus for Broiling Meats, Fish, &c.; and I hereby declare the following to be a full, clear, and exact description of the invention, such as will enable others skilled in the art to which it pertains to make use of 10 it, reference being had to the accompanying drawings, which form part of this specification.

My invention relates to an improvement in broiling stoves or furnaces.

15 Heretofore in broilers the meat has been cooked directly over or before live coals, anthracite or charred. This class of broilers have been found objectionable because of the consumption of juices, the absorption of gases 20 from the fuel, and the intense heat to which the operator is subjected.

The object of my invention is to provide a 25 broiler of such construction that the meats shall retain their juices, shall be free from all gases, and such that the heat thrown out shall not be intense; also, such that any escaping 30 greases may be saved and not consumed.

Figure 1 is a half front elevation and half-section. Fig. 2 is a half-plan and half-section. Fig. 3 is an end elevation. Fig. 4 is a cross-section.

My invention consists of a fire-box, A, provided with doors, shaking and dumping grates, ash-pan, &c., and properly lined with fire-bricks. 35 From either side of the fire-box a main flue, B, passes over inclosed compartments C, thence by return-flue D, back of said main flue and compartments, to the back of the fire-box, and by means of a pipe to the chimney. The 40 return-flue is provided with dampers and with doors E, for cleaning both the main and return-flues. The top and front of the flue over compartments C is protected by a covering of asbestos cement, M, to prevent radiation, 45 while the back of the main flue and upper part of compartments C are protected by the re-

turn-flue. The compartments C are provided with doors F, above the level of which are gridirons G for the meat, which gridirons are provided with tight fronts, rollers, and wooden 50 handles. In the bottom of the compartments C are placed either pans H, supplied with water through pipe I and drained through pipe J, or some arrangement of inclined planes K, of some non-conducting material, with perfectly 55 smooth faces, to receive the dropping grease from the gridirons above. The water, kept fresh by a new supply, provided as above, (or the non-conducting material,) not absorbing intense heat, the grease does not burn, but 60 may be conducted to tanks through pipes J J.

From the foregoing it will be understood that the operation of my broiler is not dependent upon any fixed dimensions or number of compartments, which may be one, two, three, 65 or four, &c., arranged either on one side or both sides of fire-box.

I do not limit myself to any particular construction of any of the parts as shown in the drawings.

The return-flue may be either over or back 70 of the main flue, and thus protect the top, while the back is protected by asbestos cement.

Having thus described my invention, what I claim as new, and desire to secure by Letters Patent, is—

1. In an apparatus for broiling meats, &c., the combination of the broiling-chamber C, having a door, F, the top heating-flue, B, the movable gridiron G, and the grease-receptacle arranged at the bottom of the broiling-chamber, in combination with a furnace, A, as and for the purpose set forth.

2. The combination of the main flue B, having non-conducting covering and front facing, 85 M, and the return-flue D, with the broiling-chamber C and gridiron G, as herein set forth.

H. M. KINSLEY.
